ASSEMBLED STRUCTURE

Caleb Ringle, Jersey City, N. J.

Application March 9, 1939, Serial No. 260,732

7 Claims. (Cl. 108—16)

This invention relates to building structures such as walls, skylights, roofs and the like and has for its objects, among others, to provide a new structure and a new method of assembling the same.

The invention, while capable of other uses in other environments, is particularly adapted to be advantageously employed in the construction and assembly of corrugated glass roofs and I have therefore illustrated it so applied.

Referring to the drawings, which show what I now consider to be preferred embodiments of the invention:

Figs. 1 to 4 are sectional detail elevations which, when arranged in series, show the cross-section of a roof structure embodying my invention.

Figs. 5 and 6 are detail sectional elevations taken on the lines 5—5 and 6—6, respectively, of Fig. 2 and Fig. 3.

Fig. 7 is a perspective view of one of the flanged clips constituting a part of the structure.

According to my invention, all of the parts of the roof structure are shop-made, or factory-made, and of such size as to be readily transported to the building to which the roof is to be applied. Substantially all of the individual parts are of standard sizes and may be parts kept in stock and later assembled to build roofs on buildings of different overall sizes. The design and construction of the parts are such that they may be readily assembled at the building to which the roof is to be applied, with a minimum amount of labor and scaffolding, and with comparatively simple tools.

The particular roof shown in Figs. 1 to 7 comprises corrugated glass sheets, battens or cap strips, inner strips, flanged clips, and also the more or less usual bolts, washers, packing strips, etc.

The corrugated glass sheets or panels 10 are of common and well known construction.

The inner strips 11 are all substantially alike so that description of one will suffice for all. Each inner strip 11 is constructed of suitable metal, curved in cross-section to conform with the adjacent surfaces of the sheets 10 with which it will ultimately cooperate, and of a length substantially equal to that of the same glass sheets 10. Each inner strip 11 is provided at each of its ends with a hole 12, and with spaced bolts 13 extending through it from the concave side, which bolts 13 are suitably secured to the strip 11 as by soldering their heads to the under or

concave surface of the strip, for purposes hereinafter appearing.

The battens or cap strips 14 are also like unto each other, except those used at the eaves of the roof, so that a description of one will suffice for all. Each batten strip 14 is constructed of suitable metal, curved in cross-section to conform to the adjacent surfaces of the glass sheets 10 which it will ultimately overlie, and of a length which need not be greater than that of such glass sheets. The particular type of cap strip shown is offset at one end, as indicated at 15, to conform to the structure which it will ultimately conceal. Each cap strip is provided with holes 16 adapted to receive bolts 13 and 20, as hereinafter described. The strips 14 to be used at the eaves of the roof are not offset like the others but are merely slightly flanged down at one end.

The flanged clips 17 are all of the same configuration as the inner strips 11 except that they are provided with the upwardly extending flanges, are comparatively short, and preferably constructed of heavier gauge metal. While in my type of roof, the clips 17 may be made integral with, or otherwise secured to the battens 14 at or adjacent to the ends of the battens 14 which are opposite the ends which are offset at 15, I prefer to use separate flanged clips 17 and to provide each of them with a hole 18.

The roof structure illustrated comprises also bolts 20, lead washers 21, bent washers 22, asphaltic sealing strips 23, metallic glass-supporting angles 24, clips 40, lead cushions 25, asphalt felt strips 26, asphaltic cushions 27, and metallic supports 28 for certain of the asphaltic sealing strips.

All of the parts 10 to 28 inclusive are made in one or more shops or factories.

By constructing the battens 14 and inner strips 11 as shown and described, i. e. of substantially the same length as the individual glass sheets with which they are to be used, the parts may be readily transported from the shop to the job.

As stated, each of the inner strips 11 is of substantially the same length as the individual glass sheets which it will ultimately underlie, and each inner strip 11 has its bolts 13 secured to it at the factory or shop, as by there soldering the bolts 13 to their inner strips in the position with respect thereto which they will ultimately occupy in the finished roof.

After the parts have been constructed, as above described, they are transported to the building

or site of the roof and may be assembled substantially as follows.

The bolts 20 are inserted through suitable holes, drilled or otherwise provided in the roof 5 purlin members 30, 31 (Figs. 1 and 2), along the entire length of the purlin members. After the glass supports 24 (and, if desired, also a suitable downwardly extending flashing 29) has been slipped over the bolts 20 above the purlin members 30 (Fig. 1), suitable holes having been provided in the supports 24 for that purpose, the bolts 20 are rigidly and securely locked to the purlin members 30 by nuts screwed home against the upper surfaces of the bases of the supports 10 24. Asphaltic felt cushion strips 27 are slipped over the bolts 20 (Fig. 2) along purlin members 31 and the bolts 20 are then rigidly and securely locked to their purlin member 31 in manner similar to that above described with respect to the 15 mounting of the bolts 20 on the purlin member 30 (Fig. 1). The support 28 is then placed in position to receive the asphaltic sealing strip 23 and the latter applied along the eave purlin 30. The lead cushions 25 may now be placed in position 20 25 against the flanges of the glass supports 24. The inner strips 11 are now mounted between the purlin members 30, 31 (Figs. 1 and 2) by simply slipping one end of each strip 11 over a corresponding one of the row of bolts 20 near the 30 eave of the roof (Fig. 1), and by slipping the other end of each strip over a corresponding one of the row of bolts 20 adjacent the purlin member 31 (Fig. 2). The glass sheets 10 to constitute the lowermost row are now laid on so that their 35 lower surfaces engage the sealing and cushioning strips 23, 27; so that the lower edges of the glass sheets engage the lead cushions 25; and so that the bolts 20 (secured to the purlin members 30, 31) and the bolts 13 (secured to the inner strips 11) project between adjacent edges of the 40 glass sheets (see also Figs. 5 and 6). It will be understood, of course, that the bolts 20, 20 (Figs. 1-2) now extend through the holes 12 of the inner strips 11. The lowermost row of glass 45 sheets 10 (Figs. 1-2) are now prevented from sliding downhill by the glass supports 24. The asphalt felt strips 26 are applied over the glass joints (see also Fig. 5) and battens or cover strips 14 placed over the strips 26 with the bolts 50 13 and 20 projecting through the openings in the battens 14 provided for that purpose. Lead washers 21 and nuts are now applied to all of the bolts 13 and 20 of the lowermost row of panels, and bent washers 22 also applied to the 55 bolts 20, and the nuts tightened, with this exception however, i. e. that the lead washers 21 and the top nuts are not applied at this time to those of the bolts 20 which are secured to the purlin members 31 (Fig. 2) or to the bolts 13 60 closest to those bolts 20.

The assembly of next higher row of glass sheets 10 (see Figs. 2 and 3) is now started. The flanged clips 17 are slipped over the upper ends of the bolts 13 (Fig. 2). Bolts 20 are rigidly secured to the purlin member 32 (Fig. 3) with cushion strips 27 underlying their lowermost nuts. Asphaltic filler strips 23 are applied over the lowermost row of glass sheets 10 (Fig. 2). Inner strips 11 are now mounted on the bolts 20 of the purlin members 31-32 (Figs. 2-3) in manner similar to that described above in connection with Figs. 1-2.

The second row of glass sheets 10 is now laid and the glass sheets of this row are prevented from sliding downhill by the engagement of their

lower edges with the flanges of the clips 17 (Fig. 2). These flanged clips 17 serve to prevent the second row of glass sheets 10 (Figs. 2-3) from sliding downhill, not only during assembly but permanently. The asphalt felt strips 26 and the battens 14 are now applied over the second row of glass sheets 10 in manner similar to that described above in connection with Figs. 1-2. After the battens 14 above the second row of glass sheets (Figs. 2-3) are in place, the bent washer 22 and lead washers 21 are placed on bolts 13 10 and 20 (Fig. 2) and the top nuts screwed home.

In the sub-assembly shown in Fig. 2, it will be noted that the lower ends of the battens 14, which are offset at 15, extend downhill to receive the 15 adjacent bolts 13 of the first or lower row. When so offset, the lower ends of the battens 14 conceal the flanged clips 17 and this may be considered, by some customers, to produce a more ornamental or decorative effect. If this particular appearance is not deemed desirable, the lower ends of the battens 14 may terminate at 15a, or 15b, or intermediate 15a and 15b, since the lower edges of the glass sheets 10 do not engage the battens 14 which overlie them, but are 20 25 prevented at all times from sliding downhill by the flanged clips 17.

If, instead of employing the flanged clips 17 (Fig. 2), reliance were placed upon the offsets 15 of the battens 14 to prevent the second row of 30 glass sheets 10 (i. e. the upper glass sheets 10, Fig. 2) from sliding downhill, it would be necessary to provide some temporary expedient to hold the second row of glass sheets 10 from sliding downhill during assembly and before their 35 battens 14 are or can be applied. The flanged clips 17 render the use of such temporary expedients unnecessary since they fulfill the function, both during assembly and also permanently, 40 of preventing downhill movement of the second row of glass sheets.

The completion of the remainder of the roof, as shown in Figs. 2-3, and Figs. 3-4, will be understood in view of the foregoing description and explanation. It will be understood, of course, 45 that instead of having one intermediate row of glass and appurtenant apparatus, as shown (Figs. 2-3), there may be as many of such sections as may be necessary or desirable.

It will be noted that the upper ends of the 50 uppermost assembly (Fig. 4) rest upon the building member 50 and are suitably anchored by clips 40.

So far as I am aware, I am the first to provide a roof construction of the type shown and described, in which all of the following features are present: (a) the parts of the entire roof structure, which is to be later secured to and supported by the purlins of the building, are shop-made or factory-made (including the fastening 60 of the bolts 13 to the inner strips 11) so as to require only assembly of the parts, and no additional fabrication thereof, at the site where the roof is to be applied; (b) none of the parts of the entire roof structure is materially longer 65 than the length of the glass sheet to be used from purlin to purlin, the inner strips 11 each being of substantially the same length as the batten strips 14, thus facilitating handling, storage, and transportation of the fabricated roof parts; (c) 70 during assembly, no temporary expedient is required to prevent a row of glass sheets from sliding downhill until its overlying battens have been applied and secured, the flanged clips 17 serving, both during assembly and permanently, to 75

prevent downhill movement of the glass, as described; and (d) during assembly of the roof, no scaffolding is required below the roof, the entire assembly being effected from the top side 5 of the roof.

In accordance with the provisions of the patent statutes, I have herein described the principle of operation of my invention, together with the apparatus which I now consider to represent the 10 best embodiments thereof, but I desire to have it understood that the apparatus disclosed is only illustrative and that the invention can be carried out by other means. Also, while it is designed to use the various features and elements 15 in the combinations and relations described, some of these may be altered and others omitted, without interfering with the more general results outlined, and the invention extends to such use within the scope of the appended claims.

20 What I claim is:

1. A roof comprising, in combination, purlins, a plurality of rows of rigid roof sheets in which each row of sheets except the highest overlaps and underlies the next higher row at a purlin 25 and in which the sheets of each row are slightly spaced, a plurality of rigid inner strips underlying the spaces between the sheets of each row and each extending from one purlin to an adjacent purlin, means securing the upper ends 30 of the inner strips to the purlins, each of said inner strips being of substantially the same length as the two spaced sheets which it underlies, upwardly extending bolts secured to each of said inner strips and held against rotation 35 thereby during assembly in the spaces between the sheets which the inner strips underlie, a plurality of batten strips overlying the spaces between the sheets of each row and through which said bolts extend, and means connected to each 40 inner strip adjacent its upper end and adjacent overlapping sheets for preventing downward endwise movement of the sheets of the next higher row of the overlapping sheets before and after the battens which overlie the sheets of the said higher row are applied.

2. A roof comprising, in combination, purlins, a plurality of rows of glass sheets in which each row of sheets except the highest overlaps and underlies the next higher row at a purlin and in 50 which the sheets of each row are slightly spaced, a plurality of series of rigid inner strips underlying the spaces between the sheets of which the strips of each series overlap at the purlins, bolts securing the inner strips to the purlins, each of 55 said inner strips being of substantially the same length as the two spaced sheets which it underlies, upwardly extending bolts secured to each of said inner strips and held against rotation thereby during assembly in the spaces between the sheets which the inner strips underlie, a plurality of series of batten strips overlying the 60 spaces between the sheets and through which said bolts extend, each of said last mentioned series comprising batten strips which overlap at the purlins and are secured thereto by the first mentioned bolts, and means comprising glass-supporting flanges connected to each inner strip adjacent its upper end and adjacent overlapping sheets for preventing downward endwise movement 65 of the sheets of the next higher row of the overlapping sheets before and after the battens which overlie the sheets of the said higher row are applied.

3. A roof comprising, in combination, purlins, 70 a plurality of rows of glass sheets in which each

row of sheets except the highest overlaps and underlies the next higher row at a purlin and in which the sheets of each row are slightly spaced, a plurality of rigid inner strips underlying the spaces between the sheets of each row 5 and each extending from one purlin to an adjacent purlin, means securing both ends of the inner strips to the purlins, each of said inner strips being of substantially the same length as the two spaced sheets which it underlies, upwardly extending bolts secured to each of said inner strips and held against rotation thereby during assembly in the spaces between the sheets which the inner strips underlie, a plurality of batten strips overlying the spaces between the sheets of each row and through which said bolts extend, and means comprising a flanged clip bolted to each inner strip adjacent overlapping sheets for preventing downward endwise movement of the sheets of the next higher row of the 10 overlapping sheets before and after the battens which overlie the sheets of the said higher row are applied.

4. A roof comprising, in combination, purlins, a plurality of rows of glass sheets in which each row of sheets except the highest overlaps and underlies the next higher row at a purlin and in which the sheets of each row are slightly spaced, a plurality of rigid inner strips underlying the spaces between the sheets of each row 15 and each extending from one purlin to an adjacent purlin, means securing the inner strips to the purlins, each of said inner strips being of substantially the same length as the two spaced sheets which it underlies, upwardly extending bolts secured to each of said inner strips and held against rotation thereby during assembly in the spaces between the sheets which the inner strips underlie, a plurality of batten strips overlying the spaces between the sheets of each row and 20 through which said bolts extend, and glass-supporting flanges extending upwardly from batten strips adjacent overlapping sheets for preventing downward endwise movement of the sheets of the next higher row of the overlapping sheets before and after the battens which overlie the sheets of the said higher row are applied.

5. The method of constructing a roof of the type described which method includes in combination, non-rotatably securing bolts to rigid strips adapted to extend from purlin to purlin, mounting a row of the strips on purlins and securing the upper ends of the strips to the underlying purlin so that the bolts extend upwardly from the strips, mounting a row of roof sheets on 50 two purlins and above the strips in spaced relationship to permit the bolts to project through the spaces between sheets, mounting battens and abutments on the bolts and over the last mentioned spaces, mounting a higher row of the first 55 mentioned strips on purlins and securing their upper ends to the underlying purlin in such position that their lower ends overlie the first mentioned row of roof sheets, mounting another row of roof sheets with their lower edges in engagement with the aforesaid abutments whereby they are prevented by the abutments from sliding downhill before the battens for the last mentioned row of sheets are applied, and thereafter mounting battens on the bolts extending from the last 60 mentioned row of inner strips.

6. The method of constructing a roof of the type described which method includes in combination, non-rotatably securing bolts to rigid strips adapted to extend from purlin to purlin, 65

mounting a row of the strips on purlins and securing both ends of the strips to the underlying purlins so that the bolts extend upwardly from the strips, mounting a row of glass sheets on two purlins and above the strips in spaced relationship to permit the bolts to project through the spaces between sheets, mounting battens and abutments on the bolts and over the last mentioned spaces, mounting a higher row of the first mentioned strips on purlins and securing both ends to the underlying purlins in such position that their lower ends overlie the first mentioned row of sheets, mounting another row of glass sheets with their lower edges in engagement with the aforesaid abutments whereby they are prevented by the abutments from sliding downhill before the battens for the last mentioned row of sheets are applied, and thereafter mounting battens on the bolts extending from the last mentioned row of inner strips.

7. The method of constructing a roof of the type described which method includes in combination, locking upwardly extending bolts to the purlins, non-rotatably securing bolts to rigid

strips adapted to extend from purlin to purlin, mounting a row of the strips on purlin bolts and thereby securing the strips to the underlying purlins so that the bolts of the strips extend upwardly from the strips, mounting a row of glass sheets on two purlins and above the strips in spaced relationship to permit the strip bolts to project through the spaces between sheets, mounting battens and abutments on the purlin and strip bolts and over the last mentioned spaces, mounting a higher row of the first mentioned strips on purlin bolts and thereby securing the strips to the underlying purlins in such position that their lower ends overlie the first mentioned row of glass sheets, mounting another row of glass sheets with their lower edges in engagement with the aforesaid abutments whereby they are prevented by the abutments from sliding downhill before the battens for the last mentioned row of sheets are applied, and thereafter mounting battens on the bolts extending from the last-mentioned row of inner strips.

CALEB RINGLE.
